OPERATING HANDLE LEVER MEANS FOR
ROTARY HAND BRAKES

Keith Williams, Buffalo, N. Y.

Application August 20, 1947, Serial No. 769,608

3 Claims. (Cl. 74—151)

1

This invention relates to hand brakes of the lever-operated type especially adapted for use on railway cars.

One object of the invention is to provide actuating means for rotating the chain-winding drum of a hand brake mechanism wherein the drum is held against rotation in brake-releasing direction by a releaseable locking dog, comprising an operating handle lever supported for swinging movement about a horizontal axis and having operative engagement with a driving member for rotating the winding drum, and being automatically disconnected from operative relation with respect to the driving member and drum when dropped to pendent position, thereby allowing for rotation of the drum independently of the operating handle lever when the dog is disengaged to effect release of the brakes.

A more specific object of the invention is to provide an actuating means, as set forth in the preceding paragraph, wherein operative engagement of the handle lever with the drum driving member is effected by gripping means carried by the lever and actuated by a toggle link connection with the same for holding the gripping means engaged with the driving member as the lever is swung in one direction and for effecting disengagement thereof upon the lever being swung in the reverse direction and also when dropped to pendent position.

Other objects of the invention will more clearly appear from the description and claims hereinafter following.

In the accompanying drawings, forming a part of this specification, Figure 1 is a side elevational view of a lever-operated hand brake mechanism embodying my improvements, showing the mechanism mounted on the end wall member of a railway car. Figure 2 is a transverse, vertical sectional view of Figure 1, looking toward the right in said figure and showing the operating handle lever mechanism in elevation. Figure 3 is a broken view similar to Figure 1, showing the operating handle lever swung upwardly. Figure 4 is a detailed view of the operating handle lever and cooperating parts, showing the gripping means in disengaged position. Figure 5 is a vertical sectional view, corresponding substantially to the line 5—5 of Figure 4. Figure 6 is a view similar to Figure 4, showing the gripping means in engaged position.

My improved operating lever means, as illustrated in the drawings, is shown as applied to a hand brake mechanism of the power-multiplying type enclosed in a housing 10 (Figs. 1 and 2) mounted on the vertical end wall 11 of a railway car and comprising the usual chain-winding drum 12 fixed to a horizontally disposed shaft 13 rotatably mounted in the housing, a gear wheel 14 fixed to the shaft 13, a driving pinion 15 meshing with the gear wheel 14 and fixed to a hori-

2

zontally disposed shaft 16 beneath the shaft 13 and also rotatably supported in the housing, a ratchet wheel 17 fixed to the shaft 16, a pivoted spring-pressed locking dog 18 engaging the ratchet wheel, and a trip lever 19 for actuating the dog.

In carrying out my invention, I provide means for intermittently rotating the shaft 15 which is geared to the chain-winding drum 12, comprising broadly a lever A (Figs. 4, 5 and 6), link members B—B swingingly supporting the lever A on the shaft 16, a locking dog C, toggle link members D—D and E—E connecting the dog to the lever A and the shaft 16, and a clutch wheel F, with which the dog C is engageable, fixed to the shaft 16.

The clutch wheel F is in the form of a disc provided with an annular set of peripheral teeth 20 and a central hub 21. The wheel F is mounted on the outer end portion of the shaft 16 which projects from the housing 10, being fixed to this shaft for rotation in unison therewith, and said projecting end of shaft being provided with a portion 22 (Fig. 5) of square cross section and the hub 21 of the wheel F having an axial opening 23 of square cross section fitting the portion 22 of the shaft. Inwardly of the section 22, the shaft 16 has a bearing section 24 of reduced diameter, the diameter of this section being preferably at least as great as the diagonal measurement of the square portion 22. The portion of the shaft 16 outwardly of the square portion 22 is of still further reduced diameter and is threaded at its extremity, as indicated at 25, to receive a nut 26. This last named reduced portion of the shaft provides a cylindrical bearing section 27 between the square portion 22 and the threaded extremity of said shaft.

The lever A is swingingly supported on the shaft 16 by the links B—B, which have their upper ends journaled on the bearing portions 24 and 27 respectively of the shaft and their lower ends pivotally connected to the upper end of the lever A by a pivot pin 28. This pivotal connection between the lever A and the links B—B provides for a certain amount of swinging movement of the lever with respect to the links. At its pivotal connection with the links B—B, the lever is enlarged, as shown, thus providing a head portion 29. The head portion 29 is formed with an inwardly opening pocket 30 into which the lower ends of the links B—B extend, and the pivot pin 28 is supported in suitable openings in the side walls of said pocket. As shown in Figures 1, 4 and 6, the pocket 30 has the end wall thereof at the left-hand side of the head, as viewed in said figures, inclined upwardly and outwardly, thus providing a short arm 31 on said lever for actuating the toggle links D—D. The opposite end wall 32 of the pocket is substantially parallel to the longitudinal axis of the lever A and by engagement with the links B—B acts as a limiting

stop to restrict swinging movement of the lever to the right with respect to the links B—B.

The locking dog C is in the form of a block carried on a pivot pin 32 extending through the toggle links D—D and E—E. Pin 32 is fixed against rotation in the lower ends of the links E—E, as by welding, and the locking dog C is fixed against rotation on the pin 32 in the same manner. Thus the locking dog C is maintained in circumferential alignment with the clutch wheel F. The upper ends of the links E—E are pivotally connected to the pivot pin 32.

The lower ends of the links D—D are rotatably supported on the pin 28 between the links B—B with their upper ends directly embracing the dog C at opposite sides. The upper ends of the links E—E are swingingly supported on the shaft 16, being provided with elongated, lengthwise extending slots 33 and 34 respectively, within which the journal or bearing portions 24 and 27 of the shaft have a sliding rotary fit, the end walls of these slots being rounded to provide true bearing engagement with the shaft. As shown in the drawings, the upper ends of the links E—E bear on opposite ends of the hub 21 of the clutch wheel F and are embraced by the links B—B, the entire assembly being held in position by the nut 26 at the outer end of the shaft 16. The lower ends of the links B—B and D—D are held properly spaced apart by interposed collars 35—35 and 36 on the pin 28. The dog C, which is actuated by the toggle links D—D, is provided with suitable teeth 37. The arrangement is such that the teeth 37 are engageable with the teeth 20 of the wheel F when the parts are in the position illustrated in Fig. 6.

In the operation of my improved mechanism, in applying the brakes, the operating lever A is oscillated, thereby effecting intermittent rotation of the clutch wheel F and rotation of the drum 12 to wind the chain thereon. In swinging the lever A upwardly or to the left, as seen in Figures 1 and 4, there is also pivotal movement of the lever A on the links B—B, thereby swinging the arm 31 against the toggle links D—D, causing the latter to swing toward the links B—B and lifting the locking dog C into gripping engagement with the teeth of the wheel F, as shown in Figure 6, the dog being directed in this movement by means of the guide slots 33 and 34 of the links E—E and the cooperating bearing portions of the shaft 16. Thus, as the lever A is swung from the position shown in Figures 1 and 4 through that shown in Figure 6 toward the position shown in Figure 3, rotation is imparted to the shaft 16 and the drum 12. During the return stroke of the lever A, the same first pivots on the links B—B, thus withdrawing the arm 31 from engagement with the links D—D and permitting the dog C to drop by the action of gravity to disengage the wheel F. This swinging movement of the lever with respect to the links B—B is positively limited by the right-hand end wall 38 of the pocket 30 shouldering against the links B—B. The lever A is thus permitted to return to the pendent position shown in Figure 1 while the wheel F remains stationary, held by the locking dog engaging the ratchet wheel 17. Oscillating swinging movement of the lever A is continued, until the brakes have been applied to the desired extent.

As will be evident, when the lever A is in its pendent position, as shown in Figure 4, the dog C is free of the toothed wheel F, permitting free rotation of the latter and quick release of the

brakes when the locking dog 18 is released in the usual manner by operation of the trip lever 19.

I claim:

1. In operating means for the rotary chain-tightening element of a hand brake, the combination with a toothed wheel operatively connected to the rotary tightening element, said wheel being rotatable about a horizontal axis; of a link swingingly supported for rotation about the axis of rotation of said wheel; an actuating lever pivoted to the lower end of said link; a second link pivoted at one end to said lever; a third link pivoted at its lower end to the upper end of said second named link and supported at the upper end for swinging movement about the axis of rotation of said wheel, said last named link being guided for sliding movement at its upper end; a locking dog carried by the pivotal connection of said second and third links; and a short arm on said lever engageable with said second named link by relative swinging movement of said arm and first named link to rock said second named link toward said first named link to force the dog into gripping engagement with said wheel.

2. In operating means for the rotary chain-tightening element of a hand brake, the combination with a horizontally disposed rotary driving shaft operatively connected to said tightening element for rotating said tightening element; of a toothed wheel fixed to said shaft for rotation therewith; a link swingingly supported at its upper end on said shaft; an operating lever pivotally connected at its upper end to the lower end of said link; a second link pivotally connected at its lower end to the upper end of said lever; a locking dog carried by the upper end of said second named link; and an arm on said lever thrown into engagement with said second named link by relative swinging movement of said lever and first named link for swinging said second named link toward said first named link to lift said dog into engagement with said wheel.

3. In operating means for the rotary chain-tightening element of a hand brake, the combination with a horizontally disposed driving shaft, operatively connected to said tightening element for rotating said tightening element; of a wheel fixed to said shaft for rotation therewith; a link journaled at its upper end on said shaft; a second link having a guide slot therein at its upper end within which said shaft is engaged for mounting said link for swinging and sliding movement with respect to said shaft; a third link; a pivot member secured to the lower end of said second link and connecting the lower end of said second named link to the upper end of said third named link; a locking dog secured to said pivot member and engageable with said wheel; a pivot member connecting the lower ends of said first and third named links to the upper end of said lever; and a short arm on said lever engageable with said third link for swinging the same toward said first named link by relative swinging movement of said lever and first named link to force said dog into engagement with said wheel.

KEITH WILLIAMS.
